HAIR CURLER

Mario Giannola, 911 Norwood, Melrose Park, Ill., and Joseph R. Mango, 14651 S. 49th Court, Midlothian, Ill.

Filed Mar. 30, 1965, Ser. No. 84,514

Term of patent 14 years

(Cl. D86—10)

FIG. 1 is a side elevational view of a hair curler showing our new design;

FIG. 2 is an end view; and

FIG. 3 is a view in section taken along line 3—3 of FIG. 1.

We claim:

The ornamental design of a hair curler, as shown.
